(57) CLAIM

We claim the ornamental design for the French press, as shown and described.

DESCRIPTION

FIG. 1 is a top perspective view of a French press showing our new design;

FIG. 2 is a front view thereof;

FIG. 3 is a rear view thereof;

FIG. 4 is a right-side view thereof, a left-side view being a mirror image;

FIG. 5 is a top view thereof; and,

FIG. 6 is a bottom view thereof.

Broken lines in the drawing depict portions of the invention that are not part of the claimed invention.
